US0D1038742S

(12) **United States Design Patent** (10) **Patent No.:** **US D1,038,742 S**
(45) **Date of Patent:** **** Aug. 13, 2024**

(54) **CASTER**

(71) Applicant: **Fujian Secure Medical Technology CO., LTD**, Fuzhou (CN)

(72) Inventors: **Yebing Jie**, Fuzhou (CN); **Xiaolin Shen**, Fuzhou (CN); **Jingduan Chen**, Fuzhou (CN)

(73) Assignee: **Fujian Secure Medical Technology CO., LTD**, Fuzhou (CN)

(**) Term: **15 Years**

(21) Appl. No.: **29/893,768**

(22) Filed: **Jun. 2, 2023**

(30) **Foreign Application Priority Data**

Dec. 28, 2022 (CN) 202230866573.8

(57) **CLAIM**

The ornamental design for a caster, as shown and described.

DESCRIPTION

FIG. 1 is a front view of a caster showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines in the drawings depict portions of the caster that form no part of the claimed design.

1 Claim, 7 Drawing Sheets
